DESIGN FOR AN AIR CIRCULATING UNIT

Georges Wilmet, Roslyn, N. Y., and Don F. Jones and John W. Miller, Lansing, Mich., assignors to Motor Wheel Corporation, Lansing, Mich., a corporation of Michigan

Application July 1, 1939, Serial No. 85,808

Term of patent 14 years

To all whom it may concern:

Be it known that we, Georges Wilmet, a citizen of Belgium, residing at Roslyn, in the county of Nassau and State of New York, and Don F. Jones and John W. Miller, both citizens of the United States, residing at Lansing, in the county of Ingham and State of Michigan, have invented a new, original, and ornamental Design for an Air Circulating Unit, of which the following is a specification, reference being had to the accompanying drawing, forming a part thereof.

In the drawing:

Figure 1 is a front view in elevation of the air circulating unit embodying our new design;

Figure 2 is a rear view in elevation of the unit shown in Figure 1;

Figure 3 is a side view in elevation of the unit;

Figure 4 is a top plan view of the unit; and Figure 5 is a bottom plan view of the unit.

We claim:

The ornamental design for an air circulating unit, as shown.

GEORGES WILMET.
DON F. JONES.
JOHN W. MILLER.
